MACHINE FOR THE MANUFACTURE OF GLASS ARTICLES

Filed Sept. 3, 1927

UNITED STATES PATENT OFFICE

SYDNEY HUNT, OF BIRMINGHAM, ENGLAND, ASSIGNOR TO JOHN WALKER & SONS
LIMITED, OF LONDON, ENGLAND, A BRITISH COMPANY

MACHINE FOR THE MANUFACTURE OF GLASS ARTICLES

Application filed September 3, 1927, Serial No. 217,442, and in Great Britain June 15, 1927.

This invention relates to machines for the manufacture of glass articles and refers more particularly to that type of such machines in which a parison or equivalent mould is periodically brought into contact with molten glass, contained in a tank or pot, and in which a knife is provided adapted to be moved across the orifice of the parison mould or the like in order to sever the trailing glass from the bottom of the mould.

With machines of this description it is necessary to provide means for adjusting the position in which the cutting takes place, both on account of the desirability of being able to use parison moulds or the like of different lengths and in order to obtain great accuracy in the cutting position of the knife.

The knife adapted for machines of the foregoing type is usually mounted at the bottom of a long vertical shaft rotatable in suitable bearings so that by suitable mechanism the cutting stroke can be effected at the proper time, and the object of the present invention is to provide improved means for adjusting the spindle vertically, even when the machine is operating and to enable the spindle to be held in the adjusted position. The operating and locking means are also so arranged that either a coarse adjustment or a very fine adjustment can be effected, and if necessary by the operator with the use of only one hand.

According to the general principle of the invention, the knife shaft is provided with a screw thread of suitable pitch, at some suitable portion of its length, preferably at some distance from the heat, and in the neighbourhood of a bearer arm or the like carrying one of the bearings for the knife shaft.

Associated with the bearer arm is a nut, which is restrained from longitudinal movement but which is free to rotate.

Through this nut screws the before mentioned screw threaded portion of the knife shaft.

By this means, when the nut is rotated the knife shaft is moved upwards or downwards as the case may be.

The knife shaft carries a device which is caused to rotate therewith and which device

is formed or provided with means for engagement with or disengagement from the before mentioned nut so that when the shaft has been adjusted to the required position by the rotation of the nut, further relative movement between the shaft and the nut can be prevented, by locking the device to the nut.

Although the shaft and the nut are locked together, this does not prevent the knife shaft from being turned in the ordinary manner to effect the cutting stroke by any suitable means allowing for its longitudinal movement.

In order that the invention may be more clearly understood, it will now be described with reference to the accompanying drawings and as applied to a rotatable machine of usual character furnished with parison moulds adapted to be dipped periodically into a tank containing molten glass.

In the drawings:—

Fig. 1 is a fragmentary sectional elevation shewing the knife and the method of adjusting the knife shaft.

Fig. 2 is a side elevation of a portion of Fig. 1.

Fig. 3 is a sectional plan on line 3—3 Fig. 2.

Fig. 4 shews to a smaller scale a somewhat diagrammatic view illustrating the method of disengaging the saddle piece from the nut.

Fig. 5 shews also to a smaller scale, a similar view to Fig. 1 illustrating a slightly different form of arm carrying the knife shaft and means for holding the nut from longitudinal movement.

Suitably carried by the rotatable framework of the machine not shewn in the drawings, is an arm 10 for each parison mould (not shewn). This arm 10 the outer end only of which is shewn, is of such length that the knife 9 which is carried therefrom can conveniently co-operate with the bottom of the parison mould.

At the end of this arm 10 is a bore 11 through which the knife shaft 12 passes. The upper side of the arm 10 supports a ball thrust bearing 13 which is partly located in a recess 14 coming at the under side of a nut member 15. The nut 15 is provided with a circumfer-

ential groove 20 on the exterior above which is located a flange furnished with a number of projections 16 to facilitate the manipulation of the nut, and at the top is further provided with an upwardly extending flange 17 having a number of slots or notches 18 at equiangular distances apart. The upper surface of the nut 15 is also provided with a circumferential recess 19 extending to the bore. Attached to the bearer arm 10 is a bracket 21 one portion 22 of which is adapted to enter the circumferential groove 20 on the outer surface of the nut 15 in order to hold the nut from longitudinal movement whilst not preventing it being rotated. The shaft 12 of the knife 9 is provided with a long screw thread 23 of pitch corresponding to that of the nut 15, preferably of fine pitch. This portion of the knife shaft screws into the nut and the screw threaded portion 23 is so located on the shaft that it brings the knife substantially into the region of the bottom of the parison mould.

The shaft 12 is formed with a feather way 24 and a saddle piece 25 is furnished formed with a feather 26 adapted to engage in the said feather way 24. The saddle piece 25 is kept in position on the shaft 12 by means of a metal strap 26a encircling the said shaft the ends of which strap are suitably attached to the saddle piece at 27, so that in this way the saddle piece is caused to rotate with the shaft but it is free to slide longitudinally thereon.

The saddle piece 25 is provided with two lugs 28 between which is pivoted a detent or catch 29 of suitable shape to engage the notches or slots 18 in the top flange 17 of the nut 15 before referred to, and when so engaged the lower portion 30 of the saddle piece 25 and its strap if desired enter the before mentioned circumferential groove 19 at the top of the nut, the saddle piece contacting with the nut by its weight only.

When it is required, for instance on changing moulds, to effect coarse adjustment, that is to move the knife 9 through a comparatively considerable vertical distance, the detent or catch 29 of the saddle piece 25 is disengaged from the nut 15 as shewn in Fig. 4 and turned upwards and out of the way, and then the nut 15 can be rotated as many times as required to effect this coarse adjustment.

On the other hand when it is only required to effect a fine adjustment, the nut 15 is only turned through a small angular distance as for instance that between two consecutive notches 18, thus raising or lowering the knife shaft 12 to a very slight extent.

After adjustment the detent 29 is turned down and re-engaged in one of the notches 18 thus preventing relative rotative movement between the nut 15 and the shaft 12.

When the cutting stroke is to be effected the knife shaft 12 is rotated in any usual manner

not shewn on the drawings, and the arrangement just described does not interfere with this rotary motion as the saddle piece 25 moves with the shaft 12 and the detent 29 carried by the said saddle piece causes the nut 15 also to move with the shaft 12, the thrust bearing 13 on the underside of the nut allowing for this movement.

It will be understood that although the invention has been particularly described with reference to a rotary machine provided with dipping parison moulds, it may be adapted where found desirable to other types of machines in which it is necessary to cut off trailing glass.

Having now particularly described and ascertained the nature of my said invention and in what manner the same is to be performed, I declare that what I claim is:

1. In a machine for the manufacture of glass articles and of the type comprising a parison mould and a knife carried by a rotatable shaft, for cutting off trailing glass from the bottom of the said parison mould, means for adjusting the knife shaft vertically including a screw threaded portion on the shaft, a nut screwing on to the said portion and adapted to abut against a relatively fixed portion in connection with the framework, means fixed to said framework and having engagement with said nut for maintaining the nut against movement away from the surface against which it abuts but permitting rotation of said nut, relative to the framework, and means for preventing the nut from rotating on the shaft after adjustment for the purposes set forth.

2. In a machine for the manufacture of glass articles and of the type comprising a parison mould and a knife carried by a rotatable shaft, for cutting off trailing glass from the bottom of the said parison mould, means for adjusting the knife shaft vertically including a screw threaded portion on the shaft, a nut screwing on to the said portion and adapted to abut against a relatively fixed portion in connection with the framework, means fixed to said framework and having engagement with said nut for maintaining the nut against movement away from the surface against which it abuts but permitting rotation of the nut relative to the frame, the threaded portion of the shaft extending vertically above the nut, a member slidable with respect to but constrained to rotate with the said shaft and normally contacting by its weight only with the nut, and interengaging means between the said member and the said nut for preventing their relative rotation, thus preventing the nut rotating on the shaft after adjustment for the purposes set forth.

3. In a machine for the manufacture of glass articles and of the type comprising a parison mould and a knife carried by a rotatable shaft, for cutting off trailing glass,

from the bottom of the said parison mould, means for adjusting the knife shaft vertically including a screw threaded portion on the shaft, a nut screwing on to the said portion and adapted to abut against a relatively fixed portion in connection with the framework, the screw threaded portion of the shaft extending vertically above the nut, means allowing of the rotation of the nut whilst preventing its movement away from the surface against which it abuts, a saddle piece associated by a feather and feather way with the said shaft and normally contacting by its weight only with the nut, and interengaging means between the said saddle piece and the said nut for preventing their relative rotation, thus preventing the nut rotating on the shaft after adjustment, for the purposes set forth.

4. In a machine for the manufacture of glass articles and of the type comprising a parison mould and a knife carried by a rotatable shaft, for cutting off trailing glass from the bottom of the said parison mould; means for adjusting the knife and shaft vertically including a screw threaded portion on the shaft, a nut screwing on to the said portion and adapted to abut against a relatively fixed portion in connection with the said framework, the screw threaded portion of the shaft extending vertically above the nut, the said nut being provided with a plurality of angularly spaced notches around its outer periphery, means allowing of the rotation of the nut whilst preventing its movement away from the surface against which it abuts, a member slidable with respect to but constrained to rotate with the said shaft and normally contacting by its weight only with the nut, and a pivoted detent on the member adapted to engage with any one of the angularly disposed notches on the nut for preventing the relative rotation of the said member and the nut, thus preventing the nut rotating on the shaft after adjustment, all for the purposes set forth.

5. In a machine for the manufacture of glass articles and of the type comprising a parison mould and a knife carried by a rotatable shaft, for cutting off trailing glass from the bottom of the said parison mould; means for adjusting the knife shaft vertically including a screw threaded portion on the shaft, a nut screwing on to the said portion and adapted to abut against a relatively fixed portion in connection with the said framework, the screw threaded portion of the shaft extending vertically above the nut, the said nut being provided with a plurality of angularly spaced notches around its outer surface, means allowing of the rotation of the nut whilst preventing its movement away from the surface against which it abuts, a saddle piece associated by a feather and feather way with the shaft, so that it is slidable with

respect to but constrained to rotate with the said shaft and normally contacting by its weight only with the nut, and a pivoted detent on the saddle piece, such detent being adapted to engage with any one of the angularly disposed notches on the nut, for preventing the relative rotation of the said saddle piece and the said nut, thus preventing the nut rotating on the shaft after adjustment, substantially as described.

6. In a machine for the manufacture of glass articles and of the type comprising a parison mould and a knife carried by a rotatable shaft, for cutting off trailing glass from the bottom of the said parison mould; means for adjusting the knife shaft vertically including a screw threaded portion on the shaft, a nut screwing on to the said portion and adapted to abut against a relatively fixed portion in connection with the said framework, the screw threaded portion of the shaft extending vertically above the nut, the said nut being provided with a plurality of angularly spaced notches around its outer surface, means allowing of the rotation of the nut whilst preventing its movement away from the surface against which it abuts, a member slidable with respect to but constrained to rotate with the said shaft and normally contacting by its weight only with the nut, and a pivoted detent on the member adapted to engage with any one of the angularly disposed notches on the nut, the said member being provided with a portion adapted to contact with the nut leaving the detent free to be turned into and out of engagement with any desired notch and adjustment to be easily effected with one hand, substantially as described.

7. In a machine for the manufacture of glass articles and of the type comprising a parison mould and a knife carried by a rotatable shaft, for cutting off trailing glass from the bottom of the said parison mould; means for adjusting the knife shaft vertically including a screw threaded portion on the shaft, a nut screwing on to the said portion and adapted to abut against a relatively fixed portion in connection with the said framework, the screw threaded portion of the shaft extending vertically above the nut, the said nut being provided with a plurality of angularly spaced notches around its outer surface and with a circumferential recess upon its upper surface extending to the bore, means allowing of the rotation of the nut whilst preventing its movement away from the surface against which it abuts, a saddle piece associated by a feather and feather way with the shaft, so that it is slidable with respect to but constrained to rotate with the said shaft and normally contacting by its weight only with the nut, the lower portion of the said saddle piece being adapted to enter the before mentioned circumferential groove at

the top of the nut, and a pivoted detent on the saddle piece, such detent being adapted to engage with any one of the angularly disposed notches on the nut for preventing the relative rotation of the said saddle piece and the said nut thus preventing the nut rotating on the shaft after adjustment, all substantially as and for the purposes set forth.

8. In a machine for the manufacture of glass articles, a supporting frame, a vertical shaft journaled in said frame and projecting above and below the same, the upper projecting end of the shaft being threaded, a knife fixed to the lower end of the shaft, and means for adjusting the shaft vertically and for retaining the same in an adjusted position comprising a nut threaded onto the upper projecting end of the shaft and resting on the supporting frame, the screw threaded portion of the shaft extending vertically above the nut, means connecting the frame and the nut for preventing upward movement of the latter relative to the frame and for permitting rotation of the nut relative to the shaft and to the frame, and means carried by the shaft and engageable by its weight only with the nut to lock the latter against rotation in any vertically adjusted position of the shaft.

9. In a machine for the manufacture of glass articles, a supporting frame, a vertical shaft journaled in said frame and projecting above and below the same, the upper projecting end of the shaft being threaded, a knife fixed to the lower end of the shaft, and means for adjusting the shaft vertically and for retaining the same in an adjusted position comprising a nut threaded onto the upper projecting end of the shaft and resting on the supporting frame, the screw threaded portion of the shaft extending vertically above the nut means connecting the frame and the nut for preventing upward movement of the latter relative to the frame and for permitting rotation of the nut relative to the shaft and to the frame, a sleeve mounted on the shaft above the nut and connected to the shaft for relative sliding movements but retained against relative rotary movements and normally contacting by its weight only with the nut, and means carried by the sleeve and engageable with the nut to lock the latter against rotation in any vertically adjusted position of the shaft.

10. In witness whereof I affix my signature.
SYDNEY HUNT.
